UNITED STATES PATENT OFFICE.

HERBERT VANDERBEEK, OF CANTON, OHIO, ASSIGNOR TO THE TIMKEN ROLLER BEARING COMPANY, OF CANTON, OHIO, A CORPORATION OF OHIO.

MACHINE FOR END GRINDING CONICAL ROLLS.

Application filed July 30, 1923. Serial No. 654,515.

To all whom it may concern:

Be it known that I, HERBERT VANDERBEEK, a citizen of the United States, and a resident of the city of Canton, in the county of Stark and State of Ohio, have invented a new and useful Improvement in Machines for End Grinding Conical Rolls, of which the following is a specification.

Heretofore it has been common practice, in grinding the end of a conical roll for roller bearings, to disregard the size of the large end of the finished roll and to sort the rolls after grinding. The disadvantage of this practice of grinding the end of the roll without regard to its finished size is that the size of the finished roll may fall at any point between the limits that separate one lot from the next so that most of the rolls will deviate appreciably from the standard set for said lot. The object of the present invention is to minimize the deviation of the rolls from the standards of their lot; and it consists mainly in indexing mechanism whereby the ends of the rolls are ground with reference to definite standards instead of being ground at random as heretofore. The invention also consists in providing a grinding machine with means whereby the roll to be ground is automatically so positioned with relation to the grinder that the ground roll will approximate the lot standard automatically selected by the positioning means. It also consists in the parts and in the combinations of parts hereinafter described and claimed.

In the accompanying drawing, wherein like numerals refer to like parts wherever they occur,

Fig. 1 is an elevation of a grinding machine embodying my invention,

Fig. 2 is a plan view thereof, and

Fig. 3 is a detail view of the indexing pawl and ratchet.

The machine illustrated in the accompanying drawing comprises a framework 1 wherein which the operating parts are mounted. Rotably journaled on this framework is a hollow horizontal spindle 2, which is provided with a belt pulley 3 or other suitable means whereby it is connected to a suitable source of power to be driven thereby. The spindle is slidable endwise in its bearings 4 to a limited extent. The spindle 2 is provided with a collar 5 rigidly fixed thereto so as to be movable therewith, and

this collar is adapted to bear against the end of one of the journal bearings 4 or mounting frame and thus limit the forward or return movement of the spindle, i. e. the movement towards the work feeding device hereinafter described. The spindle is normally held in its forward position as hereinafter described.

The front end of the spindle 2 is provided with a horizontally disposed seat or conical socket 8 open at its large end and adapted to receive a conical roll 9 partway therein. The roll is delivered into said seat or socket by a horizontal movement, preferably by an automatic feeding device. The feeding device illustrated in the drawing comprises a cradle in the form of a block 10 that is mounted on a slide 11 that works transversely of the axis of the spindle 2 on a suitable slideway 12 provided on the framework for said slide. The block 10 has a roll seat 13, which is open at its ends and also to a feed chute 14 by means of which the rolls are fed to the roll seat 13 on the block. Said roll seat 13 is so located as to be close to and in axial alinement with said spindle 2 and the conical roll seat 8 thereon when the slide block 10 is in its forward position and in register with the end of the feed chute when said slide block is in its rearward position. Mounted on said cradle is a reciprocatable rod 15 which when the cradle is in its forward position is in axial alinement with said spindle socket 8 and roll 9. The slide operating mechanism indicated in the drawings comprises a lever 16 secured to the slide 11 and pivotally mounted on the framework 1 and a cam 17 mounted on a shaft 18 and engaging the end of said lever 16 to operate it.

Mounted on the framework opposite the spindle is a device that is adapted to cooperate with said reciprocatable rod 15 so as to move the same endwise and thereby force the roll 9 in the roll seat 13 partway into the socket 8 of the spindle 2, whereupon the cradle is moved backwardly into position to receive a new roll, thus leaving the field clear for the movement of the grinding mechanism. The mechanism shown in the drawings comprises a slidable member 19 having a projecting ram 20 in axial alinement with the spindle 2 and rod 15 when the slide 11 is in its forward position and adapted to force it toward the spindle

- 2 to feed the roll from the roll seat 13 into the socket 8 of the spindle 2. The slide 19 is provided with an operating lever 21 that is operated by a cam 22 on the shaft 18. The ram 20 extends through a bearing member 23 that has a bushing 24 threaded therein. The bushing 24 engages a collar 25 on the ram to limit the stroke thereof and may be adjusted to 10 change the stroke of said ram. A heavy spring 26 mounted in said slidable member and engaging said ram permits movement of the slidable member after the ram has been stopped.
- 15 The grinding mechanism comprises a grinding wheel 27 rotatably mounted on a slide 28 that works in slideways mounted on the slide 11 said slideways being preferably set at such inclination with reference to 20 the axis of the spindle 2 as may be required for producing the proper angle to the front portion of the end of said roll. Suitable means may be provided for adjusting the portion of the grinding wheel on the slide.
- 25 It is noted that the movement of the slide 11 carries the grinding wheel out of the path of the ram 20 permitting a roll to be inserted in the pocket 8 and that the slide returns to its normal position as soon as the 30 roll has been inserted, bringing the grinding wheel into operative position.
- It is noted that in this construction, the movement of the slide 28 causes the grinding wheel 27 to move transversely of the 35 axis of the roll 9 along a path determined by the slideways; and consequently that the amount of grinding effected thereby is dependent upon the position of the roll. Accordingly, I have provided means for properly positioning the roll with reference to 40 the grinder. Mounted so as to be movable endwise with the spindle but incapable of rotation is a rack 29 which engages a pinion 30 which in turn is mounted on a shaft 31 disposed in a plane transversely of said 45 spindle and rotatably mounted in bearings 32 provided therefor on a fixed portion of the framework. The rack may be mounted on a sleeve 33 on the spindle that is held 50 against rotation but is keyed to the spindle to move endwise therewith. Fixed to the shaft 31 is an elongated arm 34 which carries an arcuate ratchet 35 on its end in position to cooperate with a pawl 36 that is 55 pivotally mounted on the framework or other suitable portion of the machine so as to automatically engage the teeth of said ratchet 35. By this arrangement, pressure endwise on a roll 9 seated in the socket 8 in the forward end of the spindle 2 causes said spindle to be moved backward, and this sliding movement of the spindle is transmitted through the rack 29 and pinion 30 to the ratchet 35 above mentioned; and 60 when the pressure on the roll is released, the 65

weight of the ratchet arm 34 tends to restore the pinion to its normal (forward) position; but this tendency is rendered ineffective by reason of the pawl engaging the ratchet. As the pawl is effective only when it bears 70 against the shoulder of the ratchet tooth, it will permit the spindle to move forwardly the amount required to bring the pawl into engagement with the shoulder of the tooth; that is to say, it will permit a return movement of the ratchet (and of the spindle) sufficient for the pawl to slide on the inclined portion of the ratchet tooth far enough to bring said pawl up against the shoulder thereof. Thus the pawl is effective to stop 75 the movement of the spindle at definite intervals depending upon the length of the ratchet teeth and the length of the ratchet arm.

The various positions of the spindle thus 80 determine how much of the roll is subjected to the operation of the grinding wheel. For instance, assuming that the teeth of the ratchet are numbered consecutively, the positions of the spindle that correspond with 85 these numbers, and all rolls ground when the spindle is in any particular position will have large ends of the same diameter, excepting, of course, such little variation as may be inevitable in practice. As all of the 90 rolls ground in the machine conform to one or another of the graduations of the spindle's positions, the rolls of each lot approximate the standard of that lot much more closely than under the old practice wherein the rolls were ground at random and sorted afterwards. Obviously, the indexing device 95 described admits of considerable variation in construction even without sacrificing the advantage of having such indexing effected automatically by the roll.

100 My machine is provided with a knock-out device that automatically ejects the the ground roll from the spindle socket into a distributing machine, that is correlated with the position of the spindle so that the roll ground in a given position of the spindle will be ejected into the proper chute or receptacle for rolls of each size.

110 The device illustrated in the accompanying drawing for ejecting a roll from the spindle socket comprises a rod 37 located axially in the spindle 2 and projecting from the rear end thereof. The knock-out rod is provided with an operating lever 38 that is 115 operated by a cam 39 on the shaft 18. The knock-out rod 37 has an extension 40 that is secured to the end of the pawl 36 so that when the roll has been ejected from the spindle, the pawl is moved away from the ratchet, thus permitting the spindle to move 120 forward.

125 Any suitable means may be used for properly correlating the distributing chutes with the spindle. In the accompanying drawing,

the chutes 41 corresponding with the several positions of the spindle are mounted on a rotatable drum 42 which is operatively connected to the spindle indexing mechanism to receive motion therefrom. A link 43 is secured to the ratchet arm 34 and to the end of a lever 44 that is pivotally secured to the framework. The other end of the lever 44 is connected with an arm 45 that is secured to the drum; so that as the ratchet arm is moved, the drum is rotated.

I do not wish to be limited to the mechanism hereinbefore described as my invention admits of great variation from the 15 construction shown.

What I claim is:

1. In a machine of the kind described, a work positioning means comprising a rotatable work holder slidable axially from normal position, and automatic means for indexing said work holder longitudinally according to the size of the work and keeping said work holder in its indexed position throughout the operation on the work in 25 said holder.

2. In a machine of the kind described, a work positioning means comprising a rotatable work holder slidable axially from normal position, and work-controlled means for indexing said work holder longitudinally at graduated positions, and means for keeping said work holder at a definite graduated position throughout the operation on the work in said holder.

3. A machine for end-grinding rolls comprising a rotatable spindle having an axial roll seat in its forward end, yieldable means for holding said spindle in forward position, automatic means for indexing said spindle longitudinally according to the size of the work at graduated positions, and means for keeping said roll seat at a definite graduated position throughout the operation on the roll therein.

4. A machine for end-grinding rolls comprising a rotatable spindle having an axial roll seat in its forward end, yieldable means for holding said spindle in forward position, means for pushing a roll into said seat and thereby sliding said spindle backwardly to an extent depending on the distance said roll projects out of said roll seat, automatic means for indexing said spindle longitudinally according to the size of the roll, grinding means slidable transversely of the axis of said spindle, and means for keeping said roll seat in definite indexed position throughout the operation on the roll in said seat.

5. In a machine of the kind described, a work positioning means comprising a rotatable work holder slidably axially from normal position, means for returning said work holder to normal position, means operable endwise against the work in said holder to

slide said holder to an extent depending on the length of the portion of the work that projects endwise beyond said holder, and means for stopping the return movement of said work holder short of its normal position.

6. In a machine of the kind described, a work positioning means comprising a rotatable work holder slidable axially from normal position and means for returning said work holder to normal position, means operable endwise against the work in said holder to slide said holder to an extent depending on the length of the portion of the work that projects endwise beyond said holder, and means for limiting the return movement of said work holder, said limiting means being set by the work at graduated intervals.

7. A machine for end-grinding rolls comprising a rotatable spindle slidable axially from normal position and having an axial roll seat in the forward end thereof, and means for indexing said spindle longitudinally, said indexing means comprising a member operatively connected to said spindle to be moved by the longitudinal movement thereof and a second member adapted upon the forward movement of said spindle to interlock with said first member.

8. A machine for end-grinding rolls comprising a rotatable spindle slidable axially from normal position and having an axial roll seat in the forward end thereof, and means for indexing said spindle longitudinally, said indexing means comprising a ratchet operatively connected to said spindle to be moved by the longitudinal movement thereof and a pawl adapted upon the forward movement of said spindle to interlock with said ratchet and stop such forward movement.

9. A machine for end-grinding rolls comprising a rotatable spindle slidable axially from normal position and having an axial roll seat in the forward end thereof, means for indexing said spindle longitudinally and means for knocking out the roll from said roll seat, said indexing means comprising a member operatively connected to said spindle to be moved by the longitudinal movement thereof and a second member adapted upon the forward movement of said spindle to interlock with said first member, said second member being operatively connected to said knock-out means to be actuated thereby to disengage said first member.

10. A machine for end-grinding rolls comprising a rotatable spindle slidable axially from normal position and having an axial roll seat in the forward end thereof, roll assorting means operatively connected to said spindle to be controlled by the longitudinal movement thereof, and means for indexing said spindle longitudinally, said

indexing means comprising a member operatively connected to said spindle to be removed by the longitudinal movement thereof and a second member adapted upon the 5 forward movement of said spindle to interlock with said first member to stop such forward movement.

11. A machine for end-grinding rolls comprising a rotatable spindle having an axial 10 roll seat in its forward end, yieldable means for holding said spindle in forward position, means for inserting a roll into said seat and thereby moving said spindle endwise, means for indexing said spindle longitudinally, 15 and grinding means slidable transversely of the axis of said spindle, said roll-inserting means having a constant stroke whereby the endwise movement of said spindle varies with the extent to which the roll projects 20 therefrom.

12. A grinding machine comprising a rotatable member having a conical socket in one end thereof adapted for conical rollers to enter partway and frictionally engage the 25 wall thereof, said rotatable member being slidable endwise, yielding means tending to keep said member at one end of its sliding movement, means for locking at predetermined points said member against sliding, 30 means for distributing ground rolls operatively connected with said locking means to

be set thereby, means for grinding the end of a roll that projects beyond a predetermined distance from said socket, and means for ejecting the ground roll from said socket 35 to the distributing means.

13. In a machine of the kind described, a work positioning means comprising a rotatable work holder slidable axially from normal position, means for returning said work holder to normal position, against the work in said holder to slide said holder to an extent depending on the length of the portion of the work that projects endwise beyond said holder, means for changing the 45 stroke of said reciprocable member and means for limiting the return movement of said work holder.

14. In a machine of the kind described, a work positioning means comprising a rotatable work holder slidable axially from normal position, automatic means for indexing said work holder longitudinally according to the size of the work, means for distributing the finished work operatively connected with 55 said indexing means to be set thereby, and means for ejecting the work from said work holder to said distributing means.

Signed at Canton, Ohio, this 26th day of July, 1923.

HERBERT VANDERBEEK.
